DIRECTIONAL TUNING INDICATOR

Alfred W. Barber, Flushing, N. Y.

Application January 26, 1939, Serial No. 252,898

2 Claims. (Cl. 250—40)

My present invention relates to carrier wave receivers. More particularly it relates to a system for indicating correct tuning conditions in such a receiver and for indicating, when incorrectly tuned, the direction in which the receiver should be tuned to obtain correct tuning.

One object of my present invention is to provide improved tuning indicator means in tunable carrier wave receivers. Another object is to provide tuning indication means which indicate when the receiver is mistuned and in which direction it is mistuned. A particular object is to provide a tuning indicator showing a pattern which indicates correct tuning and which moves in the same direction as the tuning control.

Before the inception of automatic volume control in radio and other tunable carrier wave receivers, tuning was accomplished, for the most part, by ear. The application of automatic volume control to receivers, however, made it difficult to tune correctly by ear due to the fact that the sensitivity of such a receiver varies in passing thru a signal and thus gives a substantially constant output over a range on either side of resonance. This inability to tune by ear has led to various visual devices to aid in the correct tuning of a receiver. Most of these tuning aids make use of the fact that the plate and screen currents of automatic volume controlled amplifying tubes varies in accordance with their gain and hence indicate by minimum current the minimum gain or true tuning point of the receiver. These devices indicate by a maximum meter deflection or similar means the correct tuning point. However, mistuning whether above or below the desired point gives the same indication. The same result to two causes is confusing to the senses. Also band-pass systems are not easily tuned since there is no definite maximum response point. I propose to overcome these and other tuning difficulties.

My present invention is of means for indicating resonance and mistuning in such a way that high and low tuning is indicated and differentiated. In use this indicator has the great advantage that tuning in one direction has a different effect on the tuning indication than tuning in the other direction. The senses quickly learn to associate the corresponding effects and causes enabling more natural and easy use of tuning indicators. One way in which I carry out this directional tuning indication is to indicate the voltages and phases of primary and secondary of a pair of coupled circuits by

means of a cathode ray tube. Various patterns are obtained and in general they may be so formed that they appear to rotate. By observing the proper polarity thru the system this rotation may be made to take place in the same direction as the rotation of the tuning knob, adding still further to the naturalness of the system. An additional advantage of my system is that it may be applied to band-pass systems as readily as to sharp response systems. This allows tuning variable selectivity systems in their expanded condition as accurately as in a contracted condition. The accuracy of indication is very high making the system of advantage in such devices as wave meters or frequency monitors.

The following description when taken in connection with the drawings will serve to point out more specifically how my new tuning indicator operates.

In the drawings:

Fig. 1 shows a complete radio receiver embodying one form of my invention.

Fig. 2 shows various cathode ray-tube patterns which may be obtained from the system shown in Fig. 1.

Fig. 3 shows a modified form of my invention.

Fig. 4 shows additional cathode ray-tube patterns.

Fig. 5 shows an additional form of my invention.

In Fig. 1 I have shown a superheterodyne radio receiver connected to an antenna A and a ground G. It consists in a first detector 1, an intermediate frequency amplifier 2, a second detector 3, an audio amplifier 4, an oscillator 5 and a power supply rectifier 6. A cathode ray tube 7 is connected to the receiver in such a way as to act as my directional tuning indicator. Since the receiver is conventional and well known in the art it will only be described further in its connection to my tuning indicator. The tuning indicator consists in a cathode ray tube 7 energized by a suitable power supply not shown, or from the regular receiver power supply. This tube may include a cathode, control grid, focusing anode and accelerating anode which are not shown since they may be of conventional design. While other well known means of deflection may be used I have shown four electro-static deflecting plates 8, 9, 10 and 11 arranged in mutually perpendicular pairs. One plate in each pair as 10 and 11 may be grounded as shown or connected to a suitable point of reference potential. Deflecting plate 8 is connected to primary 12

of the last intermediate frequency transformer of the receiver. This transformer may be tuned to resonance by means of the adjustable condenser 13 or by other well known means as for instance a fixed condenser and an inductance variation of primary 12. The high or plate side of primary 12 is connected by means of lead 14 thru blocking condenser 15 to deflecting plate 8. Resistor 16 may be a high resistance of the order of a few megohms providing a reference bias to plate 8. Plate 9 is connected to secondary 17 which as in the case of primary 12 may be tuned by the adjustable condenser 18 or other well known means. Plate 9 is connected to the high side of secondary 17 by means of lead 19 and blocking condenser 20. Resistor 21 functions as resistor 16 and serves to bias plate 9 and may be of the order of a few megohms resistance.

As I have shown and described the connection of cathode ray tube 7 to coils 12 and 17 the tube will indicate by a vertical beam deflection the intermediate frequency voltage across primary 12 and by a horizontal deflection the intermediate frequency voltage across secondary 17. While this method of resonance indication is not limited to any particular type or degree of coupling between primary 12 and secondary 17 I shall describe at this point its operation for the case of less than critical magnetic coupling between these coils. The receiver is tuned by the radio frequency stage condenser 22 and the oscillator condenser 21. As these condensers are varied in tuning in a signal the voltage across coil 12 will increase until it reaches a maximum when the radio frequency circuit is resonated to the signal and the sum or difference frequency between the oscillator and the signal frequency equals the intermediate frequency to which primary 12 and secondary 17 are tuned. This maximum primary voltage will produce a maximum vertical spot deflection on the cathode ray tube and with less than critical coupling between primary and secondary a smaller maximum horizontal deflection due to the secondary voltage. The secondary voltage will be 90 degrees out of phase with the primary voltage and hence the resulting pattern on the cathode ray tube screen will be an ellipse with its greater axis vertical as shown at d in Fig. 2. Now if oscillator 5 is tuned to a slightly lower frequency the phase and amplitude of the secondary voltage will change and the cathode ray tube pattern will rotate as shown by e of Fig. 2 due to the varying intermediate frequency. Further oscillator frequency decrease will produce patterns f and g and finally a single spot. Similarly if the oscillator is tuned higher than resonance the pattern will rotate in the opposite direction as shown at c, b, and a. If the control knob 22' of condensers 21 and 22 is geared to produce a decrease in frequency for a clockwise rotation the tube pattern will rotate in the direction of the control rotation.

I have found this tuning indicator to be very sensitive it being possible to tune to within plus or minus 20 cycles of resonance using an intermediate frequency of 500 kilocycles and a cathode ray tube pattern one inch high.

In Fig. 3 I have shown a modification of Fig. 1 in which the coupling between primary 12 and the secondary 17 of the intermediate frequency transformer is variable as indicated by the arrow 27 thru the two coils. This may be taken to be a portion of a variable selectivity carrier wave receiver and other means than the manual cou-

pling control may be used to vary the selectivity such as automatically controlled regenerative or degenerative feedback. The cathode ray tube is connected in the same manner to primary 12 and secondary 17 as in Fig. 1 and corresponding members have been used to indicate corresponding parts.

Fig. 4 shows patterns which are produced on the cathode ray tube screen by the system of Fig. 3 with the coupling between primary 12 and secondary 17 substantially greater than critical as may be used to produce a broad band response. At resonance a short horizontal line i indicates that the received frequency is equal to the mean response or dip point of the combined primary and secondary response. As the tuning is varied from this mean point the pattern shifts toward h or j depending on whether the tuning is higher or lower than the mean point. Patterns h and j are produced at the two maximum response points of the overcoupled system. Since the primary and secondary voltages are in phase or very nearly in phase at these three significant points the patterns are closed straight lines as shown in Fig. 4. In varying the coupling between primary 12 and secondary 17 the tuning indicator patterns assume all intermediate forms between those of Fig. 2 and those of Fig. 4.

Thus my tuning indicator indicates whether tuning is high or low and functions for all practical values of intercircuit coupling. It is particularly useful in the overcoupled cases as shown in Fig. 4 since conventional tuning indicators become inadequate in flat-topped or double peaked response systems. This tuning indicator may be applied to tuned radio frequency circuits since varying the secondary circuit tuning gives an indication quite similar to that obtained by varying the input frequency.

In Fig. 3 I have shown a switch 26 which may be used to short circuit condenser 20 thus applying the automatic volume control or detector products to plate 9 along with the radio or intermediate frequency voltage. This causes the pattern to move to the left as resonance is passed thru and adds an additional characteristic to the tuning indication.

In Fig. 5 I have shown my directional tuning indicator applied to a triple circuit transformer. A third tuned circuit consisting of coil 24 tuned by condenser 25 is coupled to primary 12 and to secondary 17 and is used to improve the selectivity characteristics of the transformer. My tuning indicator is shown connected by leads 14 and 19 across primary 12 and secondary 17 but it may be connected to any pair of these circuits. It will be evident to one skilled in the art how these circuits and modifications thereof may be applied to wavemeter and similar frequency indicating circuits.

While I have shown and described only a few systems whereby my invention may be carried out many modifications are possible within the spirit and scope of the invention as set forth in the appended claims.

What I claim is:

1. In a tunable carrier wave receiver the combination of at least two coupled circuits, a cathode ray tube including four electrostatic beam deflecting plates disposed in mutually perpendicular pairs, a thermionic vacuum tube amplifier connected to one of said circuits, capacitative coupling means connected between the last said circuit and one of said deflecting plates, a thermionic vacuum tube diode rectifier connected to

the other of said coupled circuits, capacitative coupling means connected between the last said circuit and a deflecting plate perpendicular to the last said plate, and a shorting switch connected across the last said capacitative means.

2. In a tunable carrier wave receiver the combination of at least two coupled circuits, a cathode ray tube including four electrostatic beam deflecting plates disposed in mutually perpendicular pairs, a thermionic vacuum tube amplifier connected to one of said circuits, capacitative coupling means connected between the last said

circuit and one of said deflecting plates, a thermionic vacuum tube diode rectifier connected to the other of said coupled circuits, capacitative coupling means connected between the last said circuit and a deflecting plate perpendicular to the last said plate, and a conductive connection to said diode for indicating by means of the last said plate the sum of all unrectified voltages applied to said diode plus all rectified voltages generated by said diode.

ALFRED W. BARBER.
